UNITED STATES PATENT OFFICE.

OLIVER H. HAMPTON, OF WILLIAMSBURG, INDIANA.

ACETYLENE-GAS GENERATOR.

SPECIFICATION forming part of Letters Patent No. 625,260, dated May 16, 1899.

Application filed May 5, 1898. Serial No. 679,802. (No model.)

To all whom it may concern:

Be it known that I, OLIVER H. HAMPTON, of Williamsburg, in the county of Wayne and State of Indiana, have invented a new and Improved Acetylene-Gas Generator, of which the following is a full, clear, and exact description.

The object of the invention is to provide a new and improved acetylene-gas generator which is simple and durable in construction, very safe, and arranged to automatically control the generation of gas from the calcium carbid according to the amount of gas used.

The invention consists of novel features and parts and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a sectional side elevation of the improvement on the line 1 1 of Fig. 2. Fig. 2 is a sectional plan view of the same on the line 2 2 of Fig. 1. Fig. 3 is an enlarged sectional side elevation of the generator proper and with its bell in a raised position, and Fig. 4 is a sectional plan view of the same on the line 4 4 of Fig. 3.

30 The improved acetylene-gas generator is provided with a generator A proper, and a gasometer B, having the usual bell B', arranged to rise and fall in the water contained in the tank B². The generator A is provided with

35 a tank C, having a funnel-shaped bottom C', the apex of which terminates in a valved outlet C² for discharging from time to time the slaked lime accumulating in the tank. The tank C is filled with water, in which the generator-bell D is adapted to rise and fall, said generator-bell being provided on its sides with spring-hooks D', adapted to engage a flange C³ at the upper end of the tank C to limit the upward movement of the generator-bell. The 40 hooks D' when pressed inward by hand permit of lifting the bell D out of the tank C.

In the upper portion of the bell D is arranged an air-cock E for allowing the escape of air upon starting the generation of gas, 45 and within the bell and likewise in the upper end thereof is arranged a carbide-holder F, adapted to contain a suitable amount of cal-

cium carbid. The holder F is provided with a basket F', having its bottom formed of grate-bars F² F³, arranged alternately and at different levels, as is plainly indicated in Fig. 3, to prevent the calcium carbid from accidentally dropping through the grate into the water contained in the tank C. A cap F⁴ fits over the basket F' and is provided in its top 55 with openings F⁵ for the escape of the gas generated into the upper portion of the bell. The basket F' is rigidly secured on a tube F⁶, extending downward below the lower edge of the bell D, and said tube is secured by a 60 set-screw F⁷ to a tube D², depending centrally from the bell D, said tube being provided near its upper end with apertures D³ to allow the gas to pass from the upper end of the bell into the tube, as will be readily understood 65 by reference to Fig. 3.

Into the bell-tube D² extends a pipe G, rising centrally in the tank C, above the level of the water therein, the lower end of said pipe G passing through the wall of the tank C to 70 the outside to carry at its outer end a valve G', as indicated in Figs. 1 and 2. The pipe G then passes through the wall of the gasometer-tank B² into a stand-pipe G², rising from the bottom of said tank B², above the level of 75 the water contained therein, so that the gas from the generator-bell D can flow through the pipe G and stand-pipe G² into the gasometer-bell B', from which the gas can flow through the outlet-pipe H into the service- 80 pipe H', connected with the burners.

The extreme lower ends of the stand-pipe G² and the pipe H are provided with outlet-pipes G³ and H², respectively, provided at their outer ends with valves G⁴ H³, which 85 when open permits the water of condensation accumulating in the pipes G² and H to be discharged therefrom whenever desired.

The bell B' is provided with a centrally depending rod or pipe B³, adapted to rest 90 with its lower end on the bottom of the gasometer-tank B² previous to the generation of the gas, and at or near the lower end of said pipe is held adjustably a collar B⁴, adapted to engage a weight I, held loosely on the pipe 95 B³ and adapted to rest on a support B⁵, carried on the bottom of the gasometer-tank B². The bell B' is also provided with a vent-pipe J, the lower end of which extends somewhat

above the lower edge of said bell, so that in case of an excess of gas accumulating in the bell B the latter rises to such height that the lower end of the pipe J leaves the water to allow the gas in the bell to escape.

The operation is as follows: The generator-bell D when lifted out of the tank C can be readily filled with calcium carbide by loosening the set-screw F⁷ and slipping the tube F⁶, together with the basket F', off the tube D².

Now by removing the cap F⁴ the basket F' can be readily filled with calcium carbide and the cover replaced and the entire device slipped back onto the tube D² and fastened thereon by the set-screw F⁷, as shown in the drawings. The bell is now replaced in the tank C, the tube D² being fitted to slide loosely on the pipe G. The air-cock is now opened to cause the bell D to move downward by its own weight, thus expelling the air and finally bringing the calcium carbide contained in the holder F in contact with the water in the tank C, so that gas is generated, and said gas passes from the bell through the apertures D³ into the tube D² and finally

into the pipe G and from the latter into the stand-pipe G² and to the bell B'. Now as the collar B⁴ is somewhat below the weight I the bell B' rises upon the accumulation of

gas until the said collar moves in contact with the weight, and upon further generation of the gas the bell B' rises and the collar B⁴ abuts against the weight I. The back pressure of the gas will now cause said generator-bell D to rise and move the calcium carbide

out of the water in the tank C. Now as the gas is withdrawn through the pipes H H' from the bell B' the pressure decreases and the generator-bell D sinks by its own weight to again bring the calcium carbide in contact with the water in the tank C. The above-described operation is then repeated—that is, acetylene gas is generated and flows into the gasometer-bell B', and when the pressure of the gas has

risen within this bell to the desired degree then the gasometer-bell overbalances the generator-bell, and the latter is forced upward by the pressure of the gas. As the pressure of the gas positively controls the generator-bell B and the calcium carbide carried thereby, it is evident that the carbide is lifted out of the water as soon as a sufficient quantity of gas has been generated and stored in the bell B'.

The weight I for the bell B' can be increased or diminished, according to the pressure desired at the burners, it being understood, however, that the weight must be sufficient to maintain a constant pressure as nearly as possible and as above explained.

It is evident that the gas-pressure caused by the weight of the generator-bell will remain constant throughout the entire apparatus, because whenever the pressure rises above that of the generator-bell gas generation

ceases and will at once begin again if the pressure is brought below it by using the gas, so that the pressure in the service-pipes is

always the same and is determined by the weight of the generator-bell.

When starting the machine, the valve G' is closed, and the air-cock E is opened, so that upon the first downward movement of the generator-bell D the air in the latter can readily escape, the cock then being closed and the valve G' opened to allow the gas generated to pass to the gasometer-bell, as above explained.

The tube or rod B³ is of such a length that when its lower end rests on the bottom of the tank B² then the lower edge of the bell B' is a suitable distance above the bottom of the tank, and the collar B⁴ is held such a distance below the weight I that the bell B' can rise that distance before the upward pressure against the bell tends to lift the weight I. The calcium carbide is thus held in contact with the water in the tank C until the pressure in the bell B' is sufficient to lift the weight I, and consequently a uniform pressure of gas will be maintained in the burners. All flickering of light is thus completely prevented.

By having the large pipes G² H and the drain-pipes G³ and H² for the same the gas can be rendered quite dry, thus insuring a bright light at all times.

Having thus fully described my invention, I claim as new and desire to secure by Letters Patent—

1. In an acetylene-gas generator, the combination with a tank provided with a vertical outlet-pipe having its upper end open and unobstructed, of a bell provided with a tube depending from its top and sliding on the outlet-pipe, said tube being apertured directly beneath the top of the bell, a tube fitting on the tube of the bell and having its lower end detachably secured to the lower end of the bell-tube, and a carbide-basket secured to the upper end of said tube, substantially as described.

2. In an acetylene-gas generator, the combination with a tank provided with a vertical outlet-pipe having its upper end open and unobstructed, of a bell provided with a tube depending from its top and sliding on the outlet-pipe, said tube being apertured directly beneath the top of the bell, a tube fitting on the tube of the bell and having its lower end detachably secured to the lower end of the bell-tube, a carbide-basket secured to the upper end of the said tube, and having an apertured cover, and means for limiting the upward movement of the bell, substantially as described.

3. In an acetylene-gas generator, the combination with a tank having an inwardly-projecting flange at its upper end and provided with a vertical outlet-pipe, of a bell provided with a depending tube sliding on the outlet-pipe and having its upper end apertured, a carbide-basket detachably secured within the upper end of the bell, and spring-hooks carried by the bell and adapted to engage the

flange at the upper end of the tank, substantially as described.

4. An acetylene-gas generator, comprising a gasometer the bell of which has a sliding connection with a weight normally resting on a support in the tank, a generator-tank adapted to contain water, a carbid-bell adapted to rise and fall in said generator-tank, a calcium-carbid holder removably secured in said bell and moving with the same, a fixed gas-pipe connected with the interior of the gasometer-bell and opening into a tube carried on the inside of said carbid-bell, and means, substantially as described, for limiting the upward movement of said carbid-bell, as set forth.

5. An acetylene-gas generator, comprising a gasometer the bell of which has a sliding connection with a weight normally resting on a support in the tank, a generator-tank having a vertical gas-pipe leading into the gasometer, a bell in the generator-tank and provided with a depending tube sliding on the gas-pipe and having its upper end apertured, and a carbid-basket within the upper part of the bell and detachably secured to the tube thereof, substantially as described.
